UNITED STATES PATENT OFFICE.

WALTER CLYDE JONES, OF CHICAGO, ILLINOIS.

SEPARABLE ATTACHMENT-PLUG.

1,225,337.

Specification of Letters Patent.

Patented May 8, 1917.

Application filed January 21, 1913. Serial No. 743,264.

To all whom it may concern:

Be it known that I, WALTER CLYDE JONES, a citizen of the United States, residing at Chicago, in the county of Cook and State 5 of Illinois, have invented new and useful Improvements in Separable Attachment-Plugs, of which the following is a full, clear, concise, and exact description, reference being had to the accompanying drawing, forming a part of this specification.

My invention pertains to attachment plugs of the kind known as "separable", *i. e.*, plugs which comprise two body portions separably connected together, one of which body 15 portions is adapted to be inserted in a wall socket or the like, while the other carries binding terminals for leading-in conductors. It is a desideratum in separable plugs that the outer contact of the insertible portion be 20 rotatable with respect to the remainder thereof in order to enable the plug to be inserted into a socket without twisting the conductors, and to lock the insertible portion in position in the socket, etc. Separable attachment plugs having a rotatable sleeve on the insertible portion, as heretofore constructed, have been subject to the disadvantage that the live contacts of the insertible portion were exposed, when the removable 25 portion was removed, in such a manner that an ignorant or careless person, or a child, might easily receive a dangerous electric shock by touching them, or might short circuit these live contacts by placing some metallic object against them. It is one of the principal objects of my invention to provide a separable attachment plug, the outer contact of the insertible portion of which will be rotatable, and the live contacts of which 30 will be protected, so as to reduce, to the greatest extent possible, the chance of the occurrence of accidents of the kinds mentioned above.

An attachment plug, constructed in accordance with my invention is described, by way of example, in the following specification and shown in the accompanying drawing. I wish it understood, however, that the invention may be embodied in other constructions than that described and shown, and that changes may be made in the construction which is described and shown, without exceeding the scope of my invention, as defined in the appended claims.

In the drawing, Figure 1 is an enlarged elevational view, in longitudinal section, of

a plug constructed in accordance with my invention, the section being taken on the line 1—1 of Fig. 3;

Fig. 2 is an elevational view, partly in section, the plug being shown as having been turned through an angle of 90 degrees from the position shown in Fig. 1;

Fig. 3 is a plan of the plug, looking at the top end of the insertible portion thereof; and

Fig. 4 is a plan of the removable portion looking at the top end thereof.

Like reference characters refer to like parts throughout the following specification and the several figures of the drawing.

The insertible portion of the plug, that is, the member which is screwed into the wall socket, lamp socket or the like, comprises an insulating base 10, of porcelain or other material having the requisite insulating properties, having its upper end reduced to form a shoulder 11. The base 10 is surrounded by a threaded contact, which consists of a threaded shell 12 having its top end flanged inwardly and crimped beneath the top portion of a return flange 13 formed at the upper end of a metallic sleeve 14, the lower end of which is embedded in an insulating ring 15, formed of molded rubber or the like. The threaded shell 12, 75 sleeve 14 and ring 15 together form a unit, and constitute the threaded contact of the insertible portion of the plug, this threaded contact inclosing the base 10 with the flange 13 in engagement with the shoulder 11 of the base, whereby rotation of the threaded contact, with respect to the base 10 is permitted. The threaded contact is retained in position upon the base 10 by means of a contact disk 16 which is immovably mounted on the top end of the base 10 with its outer edge overlying the flange 13 of the threaded contact. The disk 16 forms a sliding contact for the threaded contact and serves to prevent longitudinal withdrawal 80 of the latter from the base while permitting it to rotate freely on the base.

The base 10 fills substantially the whole interior of the threaded contact, and is formed with a pair of chambers 17 and 18, 105 for receiving the circuit-making contacts of the removable plug portion. These chambers are of rectangular shape in cross section and are separated by a wall 18' which terminates flush with the bottom of the base 110 10. A forked contact spring 19, constituting one of the circuit-making contacts of

the insertible portion, and having an inwardly extending boss 20 stamped in one of the arms thereof, is contained in the chamber 17. The contact 19 is held in place by means of a screw 21 which passes therethrough and through the disk 16 and base 10, the lower end of the screw entering a nut 22 situated between the arms of the contact 19. It will be seen that the screw 21 serves to retain both the contact 19 and the disk 16 in position.

The base 10 is formed, at its top end, with an extension 23, passing through a suitably shaped aperture in the disk 16 on which extension lies the center contact 24 of the insertible portion. The center contact 24 is secured in position in a manner similar to that employed for securing the disk 16; that is, a screw 21^a passes downwardly through the center contact 24 and base 10 and enters a nut 22^a located between the arms of a forked contact spring 19^a situated in the chamber 18 of the base, all these parts being similar to the screw 21, nut 22, and forked contact spring 19 described above. The forked contact spring 19^a forms the other circuit-making contact of the insertible portion.

The removable portion of the plug comprises an insulating block 25 of such a size that its top end conveniently enters the mouth of the insulating ring 15 of the insertible portion. The block 25 has embedded in the top part thereof a pair of binding plates from which extend contact tongues for engaging the forked contacts 19 and 19^a of the insertible portion when the two members of the plug are connected together, these tongues forming the circuit-making contacts of the removable plug portion. One of the binding plates lies somewhat below the top surface of the block 25, in which position it is secured by means of an ear 27' which is embedded in the material 45 of the block, the corners of the plate 26, at the end thereof remote from the ear 27', being likewise embedded. The plate 26 is provided with a binding screw 27, to which access may be had through a channel 28 formed in the top surface of the block 25. The channel 28 terminates in a passage 29 which passes downwardly through the block 25 and communicates with an internally threaded chamber in the bottom side thereof, of which chamber receives a hollow externally threaded bushing 30. As will be seen from Fig. 2, a lead conductor 31 may be passed through the bushing 30 and the passage 29 and along the channel 28 to the binding plate 26, to which it may be secured by means of the binding screw 27.

The binding plate 26 is formed with an upwardly bent tongue 32 which is adapted to enter between the arms of the forked contact spring 19 in the chamber 17. The

tongue 32 is formed with an aperture 33 extending therethrough, which aperture receives the boss 20 of the forked contact 19.

The second binding plate, 26^a, is similar to the binding plate 26 and is provided with a binding screw 27^a, to which a second lead conductor 31^a may be led through a passage 29^a and along a channel 28^a, these parts being identical with the parts 27, 31, 29 and 28 described above. The binding plate 26^a is formed with an upwardly extending tongue 32^a having an aperture 33^a, similar to the tongue 32 with its aperture 33. When the leading-in conductors 31 and 31^a are connected with the binding plates 26 and 26^a respectively, they are gripped against withdrawal by the bushing 30, the top edge of which binds, when the bushing is screwed home (Fig. 2), against the outer covers of the conductors, forcing the conductors against the side walls of the passages 29 and 29^a.

In the use of the device, the insertible portion is screwed into a wall socket, lamp socket or the like, and a sad iron, electric fan, or other translating device, is connected to the movable portion by means of the conductors 31 and 31^a. When the translating device is not in use, the removable portion is separated from the fixed portion. When the removable portion is thus separated, it is hardly possible for any person to touch both of the contacts 19 and 19^a simultaneously, since these contacts terminate below the mouths of the chambers 17 and 18, and are separated by the wall 18'. Likewise, it would be difficult for a metallic object to be accidentally placed across the contacts 19 and 19^a. When the translating device is to be used, the removable portion is connected with the insertible portion by pushing the tongues 32 and 32^a into the chambers 17 and 18 and between the arms of the forked contacts 19 and 19^a. By reason of the duplication of the parts, it is immaterial whether the tongues 32 and 32^a are made to connect with the contacts 19 and 19^a respectively, or with the contacts 19^a and 19 respectively. When the tongues have thus been connected with the forked contacts, they are detachably held in their connected position by means of the bosses 20 and 20^a engaging in the apertures 33 and 33^a. The removable portion may be connected to, or disconnected from, the insertible portion by a direct push or pull; so that, in case of an accidental pull being imparted to the lead conductor, as, for instance, by the falling of the translating device, the parts of the plug will simply separate, whereby injury to the plug, or to the socket, is avoided, and whereby the cutting off of the current from the translating device is insured. The two plugs are so constructed that they will separate in the manner described above, regardless of whether the 130

pull imparted to the lead conductors is in the proper direction—*i. e.*, in a line with the axis of the plug—or whether the pull is at an angle to the axis of the plug. The 5 rotatable outer contact of the insertible portion permits the plug to be screwed, as an entirety, into the socket, without twisting the lead conductors and also has the advantage of locking the insertible portion firmly 10 in position in the socket.

I claim—

1. In a separable attachment plug, the combination with an insertible portion comprising an insulating base, an end contact, 15 a stationary contact member at the top of said base, a threaded shell contact rotatably mounted on said base and having a sliding engagement with said stationary contact at the top of the base, a pair of separable contact members 20 mounted on said base and connected to said stationary contact member and end contact respectively, of a separable member comprising an insulating base, a pair of separable contact members mounted thereon 25 and constructed to coöperate with the separable contact members mounted on the insertible member, and binding-posts connected with said second pair of separable contact members.

2. In a separable attachment plug, the

combination with an insertible portion comprising an insulating base, a center contact mounted on the top of said base, a separable contact member oppositely disposed on said base, a connection extending through said 35 base from the center contact to the separable contact member, a stationary contact member mounted on the top of said base, a rotatable threaded shell mounted on said base and having a sliding engagement with said 40 stationary contact member, a separable contact member oppositely disposed on said base from said stationary contact member, a connection extending through said base connecting said separable contact member with 45 the stationary contact member, of a separable member comprising an insulating base, separable contact members mounted on said base and coöperating with the separable contact members mounted on the insertible portion, and binding-posts mounted on said 50 separable member and connected with the separable contact members mounted thereon.

In witness whereof, I have hereunto subscribed my name in the presence of two wit- 55 nesses.

WALTER CLYDE JONES.
